No. 754,650.

PATENTED MAR. 15, 1904.

G. GROGAN.

VEHICLE TOP SUPPORT.
APPLICATION FILED MAY 8, 1903.

NO MODEL.

Fig. 1.

UNITED STATES PATENT OFFICE.

GALEN GROGAN, OF MURRAY, KENTUCKY.

VEHICLE-TOP SUPPORT.

SPECIFICATION forming part of Letters Patent No. 754,650, dated March 15, 1904.

Application filed May 8, 1903. Serial No. 156,263. (No model.)

To all whom it may concern:

Be it known that I, GALEN GROGAN, a citizen of the United States, residing at Murray, in the county of Calloway and State of Kentucky, have invented a new and useful Vehicle-Top-Supporting Means, of which the following is a specification.

The present invention relates to means for supporting vehicle-tops in such manner as to prevent injury to them.

It is the object to provide means of this character that is practical, simple in construction, can be readily applied to a vehicle, and constitutes a support for the top which will permit the same to yield should it strike an obstruction, thus avoiding damage to said top.

It is also the object to construct this means so that it will constitute a yielding support for the top when the latter is lowered and will serve as mechanism to automatically elevate the top.

The preferred form of the invention is illustrated in the accompanying drawings and is described in the following specification.

In said drawings, Figure 1 is a side elevation of a vehicle body and top, showing the invention applied thereto. Fig. 2 is a perspective view of the supporting means, intermediate portions thereof being broken away in order to illustrate the device on an enlarged scale. Fig. 3 is a horizontal sectional view, on an enlarged scale, through Fig. 1.

Similar reference-numerals indicate corresponding parts in all the figures of the drawings.

In Fig. 1 of the drawings a body 10 is illustrated, having a seat 11, upon which is mounted a folding top. (Shown generally at 12.) This top may be of any well-known form, being provided with suitable bows 13, having the usual projecting bolts 14, constituting means for attaching the same to the seat.

The supporting means comprises angularly-disposed arms 15 and 16, the adjacent ends of which are connected by a coiled-spring portion 17, arranged to be placed around the rear bolt 14, as illustrated in Fig. 3. The coiled spring 17 is arranged to urge the arms toward each other. The arm 15 has its upper end

offset, as shown at 18, and upon this offset end 50 is pivoted a bow-clamp 19, comprising sections fastened together by means of set-screws 20 and lined with suitable material 21, which will prevent the scratching of the bow to which the clamp is applied. The arm 16 is 55 preferably angular in cross-section and is composed of slidably-associated sections, one of which (designated 16^a) is in the form of a boxing that receives the adjacent ends of the other, said section 16^a being provided with a 60 suitable eye 22, arranged to receive the front bolt 14 of the top. The arms are held against relative movement by means of a brace 23, pivoted, as shown at 24, to an intermediate portion of the arm 15 and having its other end 65 pivoted to a boxing that is slidably mounted upon the arm 16. A latch 26 is pivoted between its ends upon the boxing 25, one end being provided with a tooth 27, arranged to engage suitable shoulders or teeth 28, formed 70 upon one side of the arm 16. This latch is urged to its operative position by a suitable spring 29, bearing against its inner side and secured to the box. The other end of the latch may be provided with a suitable handle 75 30, which can be placed in convenient position for the occupant of the vehicle.

The operation of the supporting means is as follows: When the top is in upright position, it is yieldingly supported by the spring-pressed arm 15, so that should said top strike an obstruction—as, for instance, the limb of a tree or the top of a doorway—it will move backwardly against the tension of the spring, avoiding tearing or other injury. To adjust the 85 top, it is only necessary to push it backwardly to the desired position, whereupon it will be held by the latch 27 engaging behind the proper tooth of the arm 16. When the top is lowered, it will be evident that the spring 17 90 will constitute a yielding support which will prevent the breakage of the bows, and in order to elevate said top it is only necessary to draw inwardly upon the handle 30, thereby disengaging the latch and permitting the spring 95 17 to act. In practice two supports will, preferably, be employed, though but one may be used, if desired. It will be seen that the

structure is simple and can be manufactured at small cost. Furthermore, it can be applied to any well-known make of folding top.

From the foregoing it is thought that the 5 construction, operation, and many advantages of the herein-described invention will be apparent to those skilled in the art without further description, and it will be understood that various changes in the size, shape, proportion, 10 and minor details of construction may be resorted to without departing from the spirit or sacrificing any of the advantages of the invention.

Having thus described my invention, what I 15 claim as new, and desire to secure by Letters Patent, is—

1. A vehicle-top support in the form of an attachment comprising angularly-disposed swinging arms, a spring engaging the arms for

20 swinging one of the same in one direction, a connection between the arms for holding said swinging arm against movement, a bow-engaging device carried by one arm, and means for securing the other arm against movement.

25 2. A vehicle-top support in the form of an attachment comprising angularly-disposed swinging arms, a spring engaging the arms for swinging one of the same in one direction, means for holding the swinging arm against

30 movement, a bow-embracing clamp pivoted to the free end of the swinging arm, and means for securing the other arm to a vehicle.

35 3. In a vehicle-top support, the combination with a spring, of a swinging arm moved by the spring, a bow-clamp carried by the free end of the arm, and a holding device for the arm carried thereby.

40 4. A vehicle-top support in the form of an attachment comprising angularly-disposed arms, a coiled spring connecting the arms and constituting an eye that receives one of the projecting bolts of a vehicle-top, a bow-embracing clamp pivoted to the free end of one arm and arranged to slide upon the bow, the

45 other arm having an eye at its free end adapted to receive the pivot-bolt of the top.

50 5. In a vehicle-top support, the combination with angularly-disposed relatively movable arms, of a connection carried by one arm and having a slidable engagement with the other.

6. In a vehicle-top support, the combination with angularly-disposed relatively movable

arms, of a connection carried by one arm and having slidable engagement with the other, and a latch pivoted to the slidable portion of 55 said connection and engaging the arm upon which said portion slides.

7. In a vehicle-top support, the combination with an upright swinging top-engaging arm, of a brace pivoted at one end to the arm, and 60 a latch pivoted at the other end of the brace to secure it and the arm against movement.

8. In a vehicle-top support, the combination with angularly-disposed arms connected by a coiled portion, said coiled portion constituting 65 a spring and an eye to receive a fastening-bolt, of means for pivotally connecting one of the arms to a vehicle-bow, and a connection between the arms for holding the same against relative movement, said connection having a 70 slidable engagement with one of the arms.

9. In a vehicle-top support, the combination with angularly-disposed arms having an intermediate spring connection, of a brace connecting the arms for normally holding them 75 against movement.

10. In a vehicle-top support, the combination with angularly-disposed arms having an intermediate spring connection, of a brace pivoted at one end to one arm and having a 80 boxing which slidably surrounds the other arm, said latter arm having a series of teeth, and a latch pivoted on the boxing and coacting with the teeth.

11. In a vehicle-top support, the combination with an arm, comprising slidably-associated sections one of which is provided with an eye, of a top-engaging arm, and a spring for moving the top-engaging arm. 85

12. In a vehicle-top support, the combination with angularly-disposed arms, of a coiled-spring connection between the adjacent ends of the arms, a bow-clamp pivoted upon the free end of one arm, a brace pivoted to said arm, and a sliding connection between the 90 other arm and said brace.

In testimony that I claim the foregoing as my own I have hereto affixed my signature in the presence of two witnesses.

GALEN GROGAN.
